ATTORNEY

UNITED STATES PATENT OFFICE

TAZZ EZELL GRAY, OF HOLDENVILLE, OKLAHOMA

ADJUSTABLE BRACE

Application filed September 4, 1929. Serial No. 390,366.

This invention relates to a brace which is adjustable as to its length, the general object of the invention being to form the brace of two telescopic parts, with a threaded shaft 5 located in one part and engaging a nut carried by the other part, with manually operated means whereby the shaft can be turned to adjust the two parts and thus increase or decrease the length of the brace.

10 Another object of the invention is to provide each end of the brace with adjustable shoes for engaging the parts to be braced by the device.

This invention also consists in certain 15 other features of construction and in the combination and arrangement of the several parts, to be hereinafter fully described, illustrated in the accompanying drawing and specifically pointed out in the appended claim.

20 In describing the invention in detail, reference will be had to the accompanying drawing wherein like characters denote like or corresponding parts throughout the several views, and in which:—

25 Figure 1 is an elevation of the device.
Figure 2 is a side view thereof.

Figure 3 is a section on line 3—3 of Figure 1.

30 Figure 4 is a section on line 4—4 of Figure 1.

In these views, the numeral 1 indicates one member of the brace, and 2 the other member which slides within the first member. A block 3 is adjustably fastened within the member 1 by means of the bolts 4 which pass through the block and through any one of a plurality of pairs of holes 5 formed in opposing faces of the member 1. A threaded shaft 6 has one end swiveled in the block and 35 its other end passes through a nut 7 fastened in the inner end of the member 2. The shaft has a worm gear 8 thereon which is engaged by a worm 9 on a stub shaft 10 which is rotatably supported by the hangers 11 on the block 3. This shaft 10 is formed with a wrench receiving head which is engaged by a wrench passing through any one of a number of holes 12 formed in one side of the member 1, these holes 12 being so arranged 40 with relation to the holes 5 that a hole 12

will be opposite the shaft 10, no matter in what position the block 3 is arranged in the member 1.

A shoe 14 is adjustably connected with each end of the brace by means of the bolts 55 15 which are adapted to engage any one of a number of holes 16 arranged in two transverse rows in each end of the brace, the outer row being curved, as shown in Figure 1. Each shoe is provided with a substantially V-shaped 60 recess 17 for engaging the member to be braced. Of course, the shoes can be provided with other shaped recesses, if desired.

From the foregoing it will be seen that the brace can be adjusted as to its length by turning the shaft 10 to rotate the shaft 6 to cause the said shaft 6 to move the members 1 and 2 outwardly or inwardly. It will also be seen that the block 3 can be adjusted in the member 1 by placing the bolts 4 in the desired holes 5 in said member 1.

It is thought from the foregoing description that the advantages and novel features of the invention will be readily apparent.

It is to be understood that changes may be 75 made in the construction and in the combination and arrangement of the several parts, provided that such changes fall within the scope of the appended claim.

What I claim is:—

A device of the class described comprising 80 a pair of members telescopically arranged, a block arranged in one member, a screw shaft rotatably supported by the block, a nut carried by the other member and through which 85 the shaft passes, a worm gear on the shaft, a manually operated shaft supported by the block and having a worm thereon engaging the worm gear of the first shaft, the block carrying member having a plurality of holes 90 therein and bolts passing through some of the holes and through the block for adjustably connecting the block with the member and said last named member having a plurality of holes therein for permitting a tool 95 to be inserted to engage the worm shaft to turn the same.

In testimony whereof I affix my signature.
